UNITED STATES PATENT OFFICE.

IVER JAMES, OF OAKLAND, CALIFORNIA.

BRIDGE-TIMBER CONVEYER.

1,262,586.

Specification of Letters Patent.

Patented Apr. 9, 1918.

Application filed April 15, 1915. Serial No. 21,601.

To all whom it may concern:

Be it known that I, IVER JAMES, a citizen of the United States, residing at Oakland, in the county of Alameda and State of California, have invented certain new and useful Improvements in Bridge-Timber Conveyers, of which the following is a specification.

This invention relates to improvements in 10 conveyers and more particularly to a device of this character adapted to replace the longitudinal timbers of bridges, trestles, and the like. The principal object of my invention is to provide a device of this character 15 which may be inserted under the track on a bridge, to remove and replace the timbers with the least expenditure of time and effort.

Another object of my invention is to provide a device which is convenient to attach 20 to the adjacent structure and which is convenient to transport from place to place.

With these and other objects in view my invention consists in the novel construction, arrangement and combination of parts as 25 herein described and more particularly pointed out in the appended claim.

Reference being had to the accompanying drawing forming a part of this specification, 30

Figure 1 is a view in cross section through the top portion of a bridge structure showing my device in elevation in position thereon.

Fig. 2 is an enlarged view in section 35 through the conveyer adjacent the head end.

Fig. 3 is a fragmentary view with one of the side plates removed.

Referring to corresponding parts by the same numerals of reference, 1 denotes the 40 longitudinal bridge timbers on which is supported the ties 2 and on the latter the rails 3 of the railroad track. Denoted in general by 4, is my improved conveyer, consisting in detail of the longitudinal side members 5 connected throughout their length by the web member 6, this member may be conveniently formed of a structural steel channel having its flanges riveted to the side members 5. 7 denotes a conveyer chain adapted 45 to rest on the web 6 being of such width that this upper edge projects slightly above the upper edges of the side members 5. The 50

return length of this chain passes on rollers 8 pivotally mounted in the lower end of the conveyer frame. One end of the chain 55 passes around the drum or idler wheel 10, while the other end passes around the sprocket wheel 12. The latter is keyed to shaft 13, which extends through suitable bearings in the side plate 5 and has on the 60 outside of the latter the removable crank handles 15. On the opposite end the side members 5 are provided with hook shaped devices 16, these devices being adapted to engage one of the longitudinal members 1 65 and thereby hold the conveyer in position.

Adjacent the head end of the conveyer a chain 17 is attached to the side members 5, this chain being then carried downwardly and wrapped around a convenient portion 70 of the bridge structure thereby preventing this portion of the conveyer from being raised when the weight of the timber comes on the opposite end.

In use two of the conveyers are positioned 75 approximately in the manner shown in Fig. 1, and the timber to be replaced is lifted onto the lower end of the conveyer after having raised the track, as shown. Then by means of the crank handles 15, this timber 80 is conveyed to the upper part where it may be readily lifted and a new timber laid onto the conveyer and lowered into position.

It will thus be apparent that I have provided a device which quickly performs the 85 functions set forth in the beginning of the specification and while I have shown the preferred embodiment of my invention it will be understood that various changes may be made in form and construction without 90 departing from the scope of the claim.

What I claim as new and wish to cover by Letters Patent is:—

A conveyer of the character described comprising longitudinal side members, a 95 web having its edges attached to said side members near one edge of the latter and maintaining them in spaced relation, an endless conveyer chain having one flight resting upon and supported by said web, 100 spaced apart rollers mounted between the side bars and supporting the other flight of said conveyer chain, means for imparting movement to the conveyer chain, curved

timber-engaging hooks secured to the side members at one end and positioned to engage the underside of a rigidly supported timber, and a flexible securing device attached to the side members at the other end, and acting to prevent upward movement of said end.

Copies of this patent may be obtained for five cents each, by addressing the "Commissioner of Patents, Washington, D. C."

In testimony whereof, I affix my signature in presence of two witnesses.

IVER JAMES.
